UNITED STATES PATENT OFFICE

GUST W. NYQUIST, OF MINNEAPOLIS, MINNESOTA

INTERNAL COMBUSTION ENGINE

Application filed August 2, 1929. Serial No. 382,869.

My invention relates to internal combustion engines, and particularly to valve mechanism for controlling the intake of explosive mixture to the cylinders of the engine and the exhaust of spent gases therefrom. An object in particular is to provide valve mechanism for this purpose of simple and efficient construction which will not clog with carbon, which will operate smoothly without noise, and which has a minimum number of parts liable to get out of order. Furthermore, a valve is provided which does not require grinding to keep it in proper working condition.

15 The full objects and advantages of my invention will appear in connection with the detailed description thereof, and the novel features of my inventive idea will be particularly pointed out in the claim.

20 In the accompanying drawings which illustrate the application of my invention in practical form,—

Fig. 1 is a view in central vertical section showing the device applied to an air cooled engine. Fig. 2 is a fragmentary top plan view thereof. Fig. 3 is a view in central vertical section showing the device applied to a water-cooled engine. Fig. 4 is a fragmentary view taken on the line 4—4 of Fig. 7 and at an angle of 45° to the position of Fig. 3. Fig. 5 is a view partly in horizontal section and partly top plan with reference to Fig. 3. Fig. 6 is a view in horizontal section on the line 6—6 of Fig. 3. Fig. 7 is a view in horizontal section on the line 7—7 of Fig. 3. Fig. 8 is a plan view of a valve plate in exhaust position. Fig. 9 is a plan view of the plate in intake position. Fig. 10 is a plan view of the plate in compression and firing position. Fig. 11 represents a development of the cam shown in Fig. 3. Fig. 12 represents a development of the cam shown in Fig. 1. Fig. 13 is a plan view of the cam engaging member shown in Fig. 1.

45 It is to be understood that the engine may

be provided with any desired number of cylinders. Since these cylinders and the valve operating mechanism associated therewith are similar, it will be sufficient to disclose the invention in connection with one cylinder. 50 Referring to the construction shown in the drawings, the numeral 14 designates a cylinder in which works a piston 16 connected by a crank rod 18 to a crank shaft 20 mounted in bearings formed in a crank case 22. The upper portion of the cylinder is provided with the customary spark plug 24. The cylinder is provided with a head 25 in the form of a casting which has a central vertically disposed bearing 26 in which a shaft 28 is mounted. Secured to the lower end of the shaft 28 there is a valve plate 30 while a forked arm 32 is secured to the upper end of the shaft 28. The arm 32 is oscillated in a manner which will be described presently. The head 25 is provided with an intake aperture 34 which leads into an intake chamber 36 formed between the upper end of the head and a partition 38 in the head as best shown in Fig. 4. The head is also provided with an exhaust aperture 40 which leads from an exhaust chamber 42 formed between the partition 38 and the bottom member 44 of the head, and substantially surrounding the star-shaped casting 45 housing the four inlet conduits 46 all designated 46 which as will be understood from Figs. 3 and 7 extend from the intake chamber 36 through the exhaust chamber 42 and through the bottom member 44 so as to open upon the valve plate 30. The four conduits 46 are arranged 90° from each other around the bearing 26. The bottom member 44 is provided with four exhaust ports 48 which as will be understood from Figs. 4 and 7 open into the exhaust chamber 42. The four ports 48 are arranged 90° from each other and 45° from the conduits 46. 55 60 65 70 75 80 85 90 It will be noted that the upper part of the cylinder 14 and the chambers 36 and 42 in the head are surrounded by the usual water-

carrying chamber 47 adapted to be connected at 49 and 51 with the circulatory system. Thus the entire outer wall 53, surrounding the exhaust chamber 42 is water cooled. As 5 clearly shown in Fig. 7, a star-shaped casting 45 extends between the dividing wall 38 which forms the floor of inlet chamber 36 and the bottom wall 44 of the head 25. Through the center of the star-shaped casting 10 is a central opening which receives the valve stem 28 and a bushing 29 surrounding it, and the inlet ducts 46 are formed at the extremities of the legs of the star-shaped casting 45 so that the comparatively thin 15 walls of the ducts 46 lie wholly within exhaust chamber 42 and are separated from the water-cooled wall 53 thereof and wholly surrounded by exhaust chamber 48 except at their inner ends adjacent the central aperture holding valve stem 28.

A great advantage of this construction resides in the fact that the inlet gases contact with the heated wall 38, and, in passing through the ducts 46, are further not only 20 subject to the heat of the walls of said ducts, but operate to withdraw heat from the star-shaped casting and effect sufficient cooling thereof so the valve stem and bushing will not bind, although the water circulation contacts only with the upper end of the walls of 25 the central valve seat opening. The inlet gases thus are highly heated upon entering the cylinder, thus effecting perfect gasification before firing, and as an embodiment of 30 the invention, as demonstrated, entirely eliminating smoking.

By referring to Figs. 4, 8, 9 and 10, it will be understood that the valve plate 30 is provided with four openings 50 arranged 90° 40 from each other and which by oscillation of the valve plate may be made to register either with the conduits 40 or with the ports 48 or shutoff from communication with both. The manner in which this result is brought about 45 will be described first in connection with Figs. 1, 2, and 12, the cylinder shown in Fig. 1 being air-cooled for which purpose it is provided with fins 52. The forked arm 32 is engaged by a member 54 carried by one end 50 of an arm 56, the other end of which is secured to the top of a vertical rockshaft 58. This shaft is mounted in bearings 60 and 62 and has secured to its lower end an arm 64, the swinging end of which carries a cam 55 engaging member 66, the shape of which is best shown in Fig. 13. As shown in Fig. 1, the cam shaft 20 carries a cam cylinder 68 in the surface of which there is a double cam groove 70 with the two portions thereof 60 crossing each other. The member 66 fits into this groove and its shape is such as to keep it in the proper portion of the double groove so that it works in the two portions thereof one after the other successively. When the 65 member 66 is in the groove portion 72, the

shaft 58 has been rocked so that the cam plate 30 occupies the position shown in Fig. 9. Motive fluid now passes through the conduits 46 and openings 50 into the cylinder as will be readily understood from Fig. 6. The member 66 next passes into the long straight portion 74 of the groove which corresponds to the compression and firing periods, the valve plate 30 now being held in the position shown in Fig. 10 so that the openings 50 are not in communication with either the inlet or exhaust chambers.

The member 66 next passes into the portion 76 of the groove, the valve plate 30 now having been oscillated into the position shown in Fig. 8 so that the openings 50 register with the exhaust ports 48 as will be understood from Fig. 7. From the groove portion 76 the member 66 now passes along the inclined portion 78 and back to the intake portion 72, the shape of the member 66 being such as to cause it to pass the groove portion 74. It is apparent that two rotations of the crank shaft are required to produce a complete cycle of operations of the engine.

The manner in which the valve plate 30 is oscillated in the form of the invention shown in Figs. 3, 5, and 11 will now be described, it being noted that in this form, the cylinder is water-cooled for which purpose a water-passage 80 is provided as shown in Fig. 3. The forked arm 32 is engaged by a member 82 carried by one end of an arm 84, the other end of which is secured to the top of a rockshaft 86. This shaft is mounted in bearings 88 and 90 and has secured to its lower end an arm 92, the swinging end of which carries a roller 94. This roller works in a cam groove 96 formed in the surface of a cam cylinder 98 secured to a countershaft 100, mounted in bearings carried by the crank case 22. Also secured to the shaft 100, there is a gear 102 which meshes with a smaller gear 104 secured to the axial portion of the crankshaft 20. The gear ratio of the gears 102 and 104 is such that two rotations of the crank shaft are required to cause one rotation of the shaft 100. In this form of the invention, the cam groove 96 is a single groove, but the valve plate is operated into its different positions in a manner similar to that previously described. When the roller 94 is in the groove portion 106, the shaft 86 has been rocked so that the valve plate 30 is in the position shown in Fig. 9 for supplying motive fluid to the cylinder. The roller now passes into the groove portion 108 which corresponds to compression and firing periods, the valve plate 30 now being held in the position shown in Fig. 10. The roller next passes into the groove portion 110 so that the valve plate is moved into the position shown in Fig. 8 for exhaust.

I claim:

In an internal combustion engine, a cylinder, a head therefor comprising an upper inlet chamber and a lower exhaust chamber and

5 having a star-shaped casting extending between the upper and lower walls of said exhaust chamber, said casting being formed with a central opening leading into the cylinder and with a multiplicity of ducts

10 leading from the inlet chamber to the upper end of the cylinder and each having its walls substantially surrounded by said exhaust chamber, and valve means in the cylinder having an operating stem extending through

15 said central opening.

In testimony whereof I hereunto affix my signature.

GUST W. NYQUIST.
